CASING HEAD EQUIPMENT FOR BORE-
HOLES OR WELLS

Lewis Mervyn Cecil Seamark, Chagford, England

Application November 27, 1931, Serial No. 577,574
In Great Britain October 7, 1931

30 Claims. (Cl. 166—14)

This invention relates to an equipment serving as an internal blow-out preventer by which perforated or plain tubing may be inserted into bore-holes under pressure without "killing" the well as is usually done.

The invention is of special advantage when used with an external blow-out preventer or packer such as described in the specification of the co-pending applications Serial No. 483,290 dated 20th September 1930, and Serial No. 560,993 dated 3rd September 1931; in the use of which an external joint may be made around the external surface of the tubing as it is passed into or withdrawn from the bore-hole.

According to the present invention an internal joint is made within the tubing as it is run into or withdrawn from the bore-hole, by an internal plugging or jointing device adapted to be held within the tubing in a convenient position corresponding to that of an external blow-out preventer surrounding the tubing, whereby a tight joint is maintained internally as well as externally in the operation.

According to the invention moreover the internal plugging or jointing device is adapted to be held against the well pressure and in corresponding relation to the external blow-out preventer or packer mounted upon the well head. For the purpose a mandrel is provided in co-incident position above the well head, that is fixedly held to resist the well pressure and over which lengths of tubing may be passed successively for connection together and to be snubbed into the bore-hole by means such as commonly used for the purpose.

According to the invention moreover the internal plugging or jointing device essentially comprises an elastic jointing sleeve or the equivalent, which is subject to the well pressure for maintaining an effective joint, as well as to pressure mechanically applied, as for example by a split spring ring or cylinder in compression or a number of such rings or cylinders one beside or within the other, that is or are adapted to apply pressure from within the elastic jointing sleeve outwardly.

According to the invention moreover the elastic jointing sleeve is adapted to be carried by a cylindrical body part that at its upper end is provided with the means by which connection may be made with the lower end of the mandrel.

According to the invention moreover means are provided for the disconnection of the lower end of the mandrel from the internal plugging or jointing device, and for simultaneously lock-

ing the latter in position, whence it cannot be expelled under the well pressure.

The invention comprises constructional features of the internal plugging or jointing device. Thus as a means of connection of the mandrel and the cylindrical body part and for locking the device in position when the mandrel is disconnected and withdrawn the invention comprises upstanding "dogs" of two or more in number set equidistant apart and above the cylindrical body part upon or beneath which the elastic jointing sleeve is carried. The "dogs" have recesses on their inner faces in line, into which a boss or flange integrally provided at the lower end of the mandrel may enter when the "dogs" lie within the tubing. These recesses may have a rectangular cross section and may all serve also for mounting within the recesses and between the "dogs" split spring rings in compression by which all the "dogs" are normally thrust outwards. The "dogs" at or above a middle position extend outwardly to form an annular top face or shoulder that is adapted to engage beneath an inner annular flange or shoulder provided within a coupling sleeve or the equivalent which may be used to connect a length of plain tubing with the upper end of the last length of the perforated tubing inserted. The middle part of the coupling sleeve beneath the annular flange or shoulder referred to may have a bore of a diameter slightly larger than that of the tubing, whereby under the outward pressure of the split spring rings the "dogs" are pressed outward to assume their outermost position on coming to lie within the coupling sleeve referred to. The upper ends of the "dogs" are reduced and have a conical outer face at their upper end of a barbed or hook shaped section; the "dogs" in the outer position they thus assume within the coupling sleeve release the boss or flange on the lower end of the mandrel. The further snubbing-in of plain tubing may thereupon proceed without the use of the mandrel having regard to the fact that the "dogs" in the outer position they assume within the coupling sleeve prevent the outward movement of the internal plugging or jointing device under the well pressure.

The invention comprises the further features of the internal plugging or jointing device hereinafter described, as well as the features of method and apparatus that are hereinafter referred to.

The invention is diagrammatically illustrated by way of example in the accompanying drawings, in which

Figure 1 is a vertical section of the internal plugging or jointing device constructed according to the invention.

Figure 2 is a detail plan view on the line 2—2 of Figure 1.

Figure 3 is a detail plan view on the line 3—3 of Figure 1.

Figures 4 and 5 are sectional elevations of modifications in construction of the internal plugging or jointing device.

Figure 6 is an elevation showing the manner of use of the internal plugging or jointing device illustrated in Figure 1.

Figures 7 and 8 are plan views of the clamps and anchoring supports shown in Figure 6.

Figure 9 is a diagrammatic view illustrating the manner of use of the internal plugging or jointing device.

In carrying the invention into effect according to one construction the internal plugging or jointing device may consist of a cylindrical body part *a* of a diameter slightly less than the bore of the perforated or plain tubing *b* to be inserted into the bore-hole, and beneath this body part *a* a cylindrical elastic jointing sleeve *c* may be applied upon a downwardly depending concentric tubular member *d* screw-threaded into a central hole within the body part *a*. The elastic sleeve *c* may be provided with conical ends *c*¹ *c*² adapted to enter conical recesses respectively provided beneath the cylindrical body part *a* and upon a ring or washer *e* set upon the externally screw-threaded lower end of the concentric tubular member *d* and held in position by means of a nut *e*¹ applied beneath.

The elastic jointing sleeve *c* is provided with an internal annular cavity *c*² extending short of the ends of the sleeve *c*, for the reception within of a perforated cylindrical sleeve *f*, and each of the ends *f*¹ of the cylindrical sleeve *f* is advantageously provided conical to form conical cavities at each end around the tubular member *d* upon which the cylindrical sleeve *f* is applied so that thus the conical washer *e* on the tightening of the nut *e*¹ beneath it serves to transmit pressure to the upper and lower ends of the elastic jointing sleeve *c*. The cylindrical sleeve *f* may advantageously be provided with an internal annular cavity *f*² through which free passage is permitted, the cavity *f*² extending short of the respective ends *f*¹ of the sleeve *f* and with an external annular cavity *f*³ that is adapted for the reception of one or more split spring cylinders or rings *g* in compression. The latter is thus adapted to apply pressure outwardly upon the adjacent internal surface of the elastic jointing sleeve *c*. The cylindrical sleeve *f* is provided with transverse holes *f*⁴, and transverse holes *d*¹ may also be provided in corresponding or other position in the depending tubular member *d*, by which the well pressure may be transmitted to the inner face of the elastic jointing sleeve *c*, it being understood that the internal annular cavity *c*² in the elastic jointing sleeve *c* allows of free communication from the holes *d*¹ in the depending tubular member *d* to the holes *f*⁴ in the cylindrical sleeve *f*. Thus the elastic jointing sleeve *c* maintains a tight joint between its outer face and the inner face of the tubing *b* as it is passed into or withdrawn from the bore-hole.

The upper end of the body part *a* is provided with a central hole *a*¹ communicating with the central bore of the depending tubular member *d*, and at the lower end at *a*² is provided with a seat for a valve *h* whose stem extends upward and has

a helical spring *h*¹ mounted on its upwardly protruding end. This valve *h* is thus adapted to be positively actuated by means of a rod for equalizing the pressure above and beneath the plugging or jointing device, the valve *h* being also adapted to open on the application of fluid or gas pressure above the body of the plugging or jointing device higher than that of the well pressure, or of the pressure below the plugging or jointing device.

The upper face of the body *a* is provided with recesses *a*³ of an almost cylindrical form. These may for example be four in number and may be provided in two opposite pairs disposed parallel and equidistant from the centre and from each other for the accommodation of the lower ends of two or more "dogs" *i* also set in parallel and oppositely disposed pairs having their lower ends *i*¹ of partially cylindrical form. The lower ends *i*¹ of the "dogs" *i* may thus enter the recesses *a*³ in an axial movement and each of the ends *i*¹ may be provided with a peripheral groove *i*² with which the end of a grub screw *i*³ may engage as a simple means for ensuring fixity of lateral position of the respective "dogs" *i*, whereby the "dogs" *i* may thus hinge or pivot upon their lower ends *i*¹ while being held from lateral displacement.

The "dogs" *i* are co-extensive in length, and at their upper ends *i*⁴ they are reduced in section and have a conical outer face *i*⁵, and in a middle position on their outer faces the "dogs" *i* have outwardly extending parts *i*⁶, while in a corresponding position at their inner faces an open recess *i*⁷ is provided advantageously of a rectangular form. The lower face of these recesses *i*⁷ determines the position of the lower end of the mandrel *j* and the recesses *i*⁷ are thus adapted for the reception of an outwardly extending boss or flange *j*¹ at the lower end of the mandrel *j* by which the fixity of position of the internal plugging or jointing device is determined. The outwardly extending boss *j*¹ lies against the lower inwardly extending face of the recesses *i*⁷ formed at the inner faces of the "dogs" *i* in all permitted positions of the "dogs". One or two split spring rings *k* with gaps are provided in compression for accommodation within the recesses *i*⁷ formed on the inner faces of the "dogs" *i*; whereby the "dogs" *i* are normally thrust outwards in a pivotal movement on their lower ends *i*¹, but are permitted inward movement into the position they assume by contact with the tubing *b* on the tubing *b* being inserted into or being withdrawn from the bore-hole. In this position the recesses *i*⁷ on the inner faces of the "dogs" *i* are engaged by the outwardly extending boss or flange *j*¹ of corresponding form at the lower end of the mandrel *j*. The split spring rings *k* however cause the outward movement of the "dogs" *i* on the "dogs" *i* passing into a coupling sleeve *l* having a larger internal diameter than the internal diameter of the tubing *b*, whereby the outwardly extending parts of the "dogs" *i* at their outer faces engage beneath an integral shoulder *l*¹ provided in the coupling sleeve *l*, and thus the outward movement of the plugging or jointing device is prevented under the well pressure on the release of the lower end of the mandrel *j* on the outer pivotal movement of the "dogs" *i* in the manner described. By such means the outwardly extending boss or flange *j*¹ at the lower end of the mandrel *j* clears the recesses *i*⁷ on the inner faces of the "dogs" *i*, and thus the withdrawal of the mandrel *j* is permitted.

The mandrel *j* is provided of a length in excess of the lengths or sections of the tubing *b*, and at its respective ends *j*², *j*³ (Figure 6) is advanta-

geously provided with a buttress thread by which it may be held within suitable transverse clamps *m* *n* and anchoring supports for the purpose of fixedly holding the mandrel *j* in position above 5 and coincident with the well head with the lower end of the mandrel *j* engaged in the manner described by the "dogs" *i*, the latter being set into such position that the plugging or jointing device beneath, assumes a position corresponding to the 10 surrounding external blow-out preventer *p*.

For the purpose of inserting perforated or plain tubing *b* into the bore-hole the plugging or jointing device such as hereinbefore described is inserted into a length of the perforated or plain 15 tubing *b* (Figure 6) with the lower end of the mandrel *j* engaged by the "dogs" *i*, and the length of tubing *b* carrying the plugging or jointing device and the inserted mandrel *j* may be passed into the blow-out preventer *p* and into a "container" *p*¹ beneath, which is mounted upon the well head flange *p*², a suitable valve *p*³ being interposed to isolate the "container" *p*¹ from the well. The upper end of the mandrel *j* may be secured by the transverse top clamp *m* and the 20 upper end of the length of perforated or plain tubing *b* engaged by one of the clamps of the snubbing gear, whereupon the valve *p*³ on the well head is opened and the length of tubing *b* is snubbed-in. The connection and snubbing-in of 25 further lengths of perforated tubing or plain tubing *b* may then proceed as is usual.

It will be understood that by such means the mandrel *j* is held stationary as the tubing *b* is lowered into the bore-hole against the well pressure 30 sure, and that a pressure tight joint is maintained between the elastic jointing sleeve *c* and the inside of the tubing *b*, and between the packing medium in the external blow-out preventer *p* and the external surface of the tubing *b*. The external blow-out preventer *p* is preferably 35 provided of a construction such as described in the specification filed pursuant to the co-pending applications hereinbefore referred to in which the packing medium takes the form of a massive elastic sleeve *d*.

In the use of the internal plugging or jointing device, the device comprising the body *a*, the tubular member *d* and the elastic sleeve *c* and the "dogs" *i*, with the mandrel *j* are inserted 40 into a length of the perforated tubing *b*, the device with the mandrel *j* and perforated tubing *b* are then inserted into the "container" *p*¹ (Figure 9) mounted above the main valve *p*³ on the well head, the snubbing-in gear is then attached 45 to the tubing *b*, and a clamp *m* (Figure 6) is attached to the top threaded part *j*² of the mandrel *j*, this clamp *m* being held by anchoring supports *m*¹ and bolts *m*². The plugging or jointing device is then set so that the elastic jointing sleeve *c* is opposite to the massive elastic sleeve *d* or the equivalent in the external blow-out preventer *p*, the external blow-out preventer is closed on to the outside of the perforated tubing *b* and the main valve *p*³ on the well head is then opened. Thereupon the length of perforated tubing *b*, is snubbed-in until the lower 50 thread *j*² on the mandrel *j* is exposed, and the upper end of the perforated tubing *b* is then clamped in position, by the bottom "snubbing" 55 clamp of the "snubbing" gear to prevent it being blown out of the well. The clamp *n* is then put upon the lower threaded end *j*² of the mandrel *j* and this clamp *n* is then anchored to the adjacent anchoring support or clamp *o* on the 60 partly inserted tubing *b* as illustrated in Figure 6.

The clamp *m* by which the top threaded end *j*² of the mandrel *j* is held is then removed for the application of another length of perforated tubing *b*. This further length of tubing *b* is then lowered over the top of the mandrel *j* and the clamp *m* secured to the upper screw-threaded end *j*² of the mandrel *j*. The clamp *n* at the lower threaded end *j*² of the mandrel *j* is then removed. The additional length of tubing is then screwed into that already partly within the bore-hole. The snubbing-in gear is thereupon attached to the upper end of the added length of tubing. The clamp is then removed from the upper end of the length of tubing previously snubbed-in and the further length of tubing is then snubbed into the well. The operations are repeated until the required amount of perforated tubing has been snubbed-in.

The special coupling sleeve *l* such as hereinbefore described provided centrally with a bore of a slightly larger diameter than the internal diameter of the tubing *b* may be connected at the top of the last length of the string of perforated tubing, so that thus when this coupling sleeve *l* reaches the "dogs" *i*, the latter move outwardly in a pivotal movement to release the lower end *j*¹ of the mandrel *j* and to engage beneath the inwardly extending flange or shoulder *l*¹ within the coupling sleeve *l*. Thus also no further upward movement of the internal plugging or jointing device is permitted. The remaining lengths of plain tubing may now be inserted without the use of the mandrel, and the internal plugging or jointing device being fixedly set in position by the engagement of the "dogs" within the coupling sleeve, descends with the tubing.

It will be understood that the exposed internal bore of the other couplings used for connecting the sections of plain or perforated tubing are of insufficient length to accommodate the outwardly extending parts of the "dogs" *i*, which thus cannot move outwardly to release the end of the mandrel as the couplings pass the internal plugging or jointing device.

After the desired number of lengths of tubing have been inserted the pressure above and below the internal plugging or jointing device may be equalized by opening the valve *h* in the cylindrical body *a* thereof, or by pressure being applied to the flow-head. The internal plugging or jointing device can now be tripped by dropping a "go-devil" down the bore-hole, whereby the tops of the "dogs" *i* are encircled and engaged by which they are forced inward for their disengagement from the internal flange or shoulder *l*¹ of the coupling sleeve *l*.

By relieving the pressure on the tubing head the internal plugging or jointing device may be slowly forced upwards into a small container at 135 the well head in known manner and removed from the well. Alternatively it may be removed by a fishing tool without the necessity of releasing the pressure on the tubing head. It will further be understood that by the application of sufficient pressure on the tubing head to close 140 the valve *h* on the body part *a* of the internal plugging or jointing device, the latter may be forced into the bore-hole to enable the tubing to be withdrawn from the well. It may also be set in position by means of a mandrel such as *j* lowered into the tubing, it being understood that the recesses *i*⁷ on the inner faces of the "dogs" *i* render it impossible for the mandrel *j* to be withdrawn until the outward pivotal movement of 145 150

the "dogs" *i* is permitted on their passing into the special coupling sleeve *l*.

It will furthermore be understood that in running plain tubing into a well a special coupling sleeve such as *l* may be applied at the lower end of the tubing by which the internal plugging or jointing device may be secured in a corresponding position for release by a "go-devil" or fishing tool in the manner described.

10 More than one internal plugging or jointing device or unit may be used with a view to provide against damage to the elastic jointing sleeve of one of them. Thus as illustrated in Figure 4 the downwardly depending tubular member *d* of one 15 unit may be extended substantially beneath the end nut for the purpose of the connection of a further tubular member *d* upon which a second elastic jointing sleeve *c* may be mounted with an internally applied cylindrical sleeve *f* as herein- 20 before described. The connection of the lower tubular member *d* may be effected by means of a cylindrical collar *q* having a conical face *q*¹ on its underside, and the respective tubular members *d* at their lower ends may be provided with a 25 series of holes *d*³ by which the fluid pressure medium may be accessible within. It will be understood that more than two such internal plugging or jointing devices or units may be provided of substantially the same construction and connected to depend one beneath the other in the manner described, except that a valve *h* may only be provided in the uppermost device or unit.

Two or more of such internal plugging or jointing devices may be provided to depend one from 35 the other in the manner described, and each may be equipped at its upper end with a valve such as *h* as illustrated in Figure 5, that is adapted to be opened on a higher pressure applied above the valve, so that thus the internal plugging or jointing device may be forced into the well by pressure applied at the surface under conditions in which an effective joint may be maintained should one of the units of the device fail. For this purpose near the lower end of each of the downwardly depending tubular members *d* of each unit 40 a non-return ball valve *q*³ or the equivalent may be mounted in such manner that an enclosing space is provided within the bore of the downwardly depending tubular members *d*, which is 45 thus adapted for the upward passage only of a fluid pressure medium. Thus should the elastic jointing sleeve *c* of the upper unit be damaged the fluid pressure medium may pass between the tubing and the sleeve of the upper unit, thence 50 through the holes *d*³ in the downwardly protruding end of the tubular member *d* of the first unit for passage through the valve *h* in the upper end 55 of the tubular member *d* of the second unit, whereby a pressure may be imposed under which 60 an effective joint may be made of the elastic jointing sleeve with the inside of the tubing, while where the elastic jointing sleeve of the first unit is unimpaired, the fluid pressure medium may pass through the valve *h* at the upper end of 65 the first unit to maintain a pressure within the elastic jointing sleeve of the first unit. By such means the internal plugging or jointing device may be forced into the well by pressure applied at the surface and the elastic jointing sleeves may 70 be caused to pack off effectively should one or more of them fail.

It will be understood however that the use of a single unit with a ball valve or the equivalent in the lower end of the tubular member may be 75 employed.

It will furthermore be understood that an elastic jointing sleeve of india rubber may be used, but no limitation is imposed to that material.

I claim:—

1. An internal plug for tubing in pressure wells comprising a cylindrical elastic jointing sleeve, the internal cylindrical surface of which is exposed to the well pressure and mechanical means at the well head above the internal plug by which the internal plug is fixedly located and held within the tubing against upward axial thrust under the well pressure during the running-in or withdrawal of the tubing. 80

2. An internal plug for use in pressure walls comprising a body part, a cylindrical elastic jointing sleeve upon the body part, and means at the well head above the internal plug by which the body part is mechanically located and held within the tubing to resist upward axial thrust under the well pressure during the running-in or withdrawal of the tubing. 85

3. A blow-out preventer for use in pressure wells comprising a well head casing, tubing adapted to extend into the well, an external packer 100 within the casing, the external packer having an internal cylindrical elastic jointing sleeve externally exposed to fluid pressure, and being adapted for the passage through it of the tubing, and an internal plug within the tubing, the internal 105 plug having an external elastic jointing sleeve internally exposed to the well and means by which the internal plug is adapted to be fixedly held at the well head to resist axial thrust under the well pressure during the running-in or withdrawal of the tubing. 95

4. A blow-out preventer for use in pressure wells comprising a well head casing, tubing adapted to extend into the well, an external packer

110 within the casing, the external packer having an internal cylindrical elastic jointing sleeve externally exposed to fluid pressure and being adapted for the passage through it of the tubing, an internal plug within the tubing, the internal plug being adapted to be set within the tubing in 115 concentric and coincident relation with the external packer in the well head casing, the said internal plug having an external elastic jointing sleeve internally exposed to fluid pressure, means by which the internal plug is adapted to 120 be fixedly held at the well head to resist axial thrust under the well pressure during the running-in or withdrawal of the tubing, and means by which the internal and external elastic jointing sleeves are exposed to fluid pressure. 125

5. A blow-out preventer for use in pressure wells comprising a well head casing, tubing adapted to extend into the well, an external packer

130 within the casing, the external packer having an internal cylindrical elastic jointing sleeve externally exposed to fluid pressure and being adapted for passage through it of the tubing, an internal plug within the tubing, the internal plug having an external elastic jointing sleeve internally exposed to the well, and mechanical means at the well head for fixedly locating and holding against upward thrust the internal plug within the tubing under the well pressure during the running-in or withdrawal of the tubing. 135

6. An internal plug for tubing in pressure wells, comprising a body adapted for release from engagement at the well head and for free axial movement within the tubing, a cylindrical elastic jointing sleeve upon the body and means within 140

145

150

- the body by which the internal cylindrical surface of the sleeve is always exposed to the well from below the body.
7. An internal plug for tubing in pressure wells, comprising a body adapted for release from engagement at the well head and for free axial movement within the tubing, a cylindrical elastic jointing sleeve upon the body, means within the body by which the internal cylindrical surface of the sleeve is always exposed to the well from below the body, and means at the well head by which the body and sleeve are mechanically located and held within the tubing in the operation of running-in or withdrawal of the tubing.
15. 8. An internal plug for tubing in pressure wells, comprising a body adapted for release from engagement at the well head and for free axial movement within the tubing, part of which body is of tubular form and open at the lower end, and a cylindrical elastic jointing sleeve upon the tubular part, and means by which the internal surface of the sleeve is subject to the pressure of the well consisting of holes extending through the tubular part.
25. 9. An internal plug for tubing in pressure wells, comprising a body adapted for release from engagement at the well head and for free axial movement within the tubing, a cylindrical elastic jointing sleeve upon the body, means within the body by which the internal cylindrical surface of the sleeve is exposed to the well, and a valve at the upper end of the body, the valve being normally thrust upward into its closed position and being adapted to open in a downward movement on pressure applied to the valve from above the said body.
10. An internal plug for tubing in pressure wells, comprising a body adapted for release from engagement at the well head and for free axial movement within the tubing, part of said body being of tubular form and open at the lower end, a cylindrical elastic jointing sleeve upon the tubular part, the tubular part having holes therein extending therethrough by which the said sleeve is subject to the well pressure from below the body, and a valve at the upper end of the body normally closed and adapted to be open in a downward movement on pressure applied to the valve from above the said body.
50. 11. An internal plug for tubing in pressure wells, comprising a body, a cylindrical elastic jointing sleeve upon the body, the sleeve being at its ends formed with inwardly extending conical edges and having an internal annular cavity extending short of its respective ends, the cavity having conical end faces forming recesses of an acute angled cross-section, an internal cylindrical sleeve of a form corresponding to the cavity and fitting therein, means for the application of axial pressure at one end of the elastic jointing sleeve, and means within the body and within the internal sleeve by which the internal cylindrical surface of the elastic jointing sleeve is exposed to the well.
65. 12. An internal plug for tubing in pressure wells, comprising a body, a cylindrical elastic jointing sleeve upon the body, the sleeve being at its ends formed with inwardly extending conical edges and having an internal annular cavity extending short of its respective ends, the cavity having conical end faces forming recesses of an acute angled cross-section, an internal sleeve of a form corresponding to the said cavity and fitting therein, annular recesses on the internal and 75 external faces of the internal sleeve, the recesses extending short of the respective ends thereof, means for the application of axial pressure at one end of the elastic jointing sleeve, and means within the body and in the internal sleeve by which the internal cylindrical surface of the elastic jointing sleeve is exposed to the well.
13. An internal plug for tubing in pressure wells, comprising a body, a cylindrical elastic jointing sleeve upon the body having an internal annular cavity extending short of the ends of said sleeve, an inner cylindrical sleeve within the cavity, and means within the body and inner cylindrical sleeve by which the internal cylindrical surface of the elastic jointing sleeve is exposed to the well.
14. An internal plug for tubing in pressure wells, comprising a body, a cylindrical elastic jointing sleeve upon the body, means within the body by which the internal cylindrical surface of the sleeve is exposed to the well, and mechanical means for the application of pressure outwardly upon the inner cylindrical surface of the elastic jointing sleeve.
15. An internal plug for tubing in pressure wells, comprising a body, a coincident tubular part of smaller diameter depending from the body and open at its lower externally screw-threaded end, a cylindrical elastic jointing sleeve upon the tubular part, the tubular part having holes therein extending therethrough by which the said sleeve is subject to the well pressure from below the body, and means for holding the cylindrical elastic sleeve in position against the well pressure and applying axial pressure to the said sleeve comprising a nut applied upon the lower end of the tubular part.
16. A plurality of separable internal plugs in line, for tubing in pressure wells, each plug comprising a body adapted to be closed at the upper end and having a tubular lower part and a cylindrical elastic jointing sleeve upon the tubular lower part, the tubular lower part extending downwards beyond the sleeve as a means of connection with the body of the next plug beneath and having holes therein communicating between the central cavity within the tubular lower part and the surrounding annular space beneath the sleeve, substantially as hereinbefore described.
17. A plurality of internal plugs in line, for tubing in pressure wells, each plug comprising a body having a tubular lower part, a cylindrical elastic jointing sleeve upon the tubular lower part, the tubular lower part extending downwards beyond the sleeve as a means of connection with the body of the plug next beneath, and having near the lower end means of communication between the central cavity and the surrounding annular space beneath the sleeve, a valve in the upper part of the body, opening downwardly, and a non-return valve near the lower end of the tubular lower part above the said means of communication, the said non-return valve opening upwardly, substantially as hereinbefore described.
18. A plurality of internal plugs in line, for tubing in pressure wells, each plug comprising a body having a tubular lower part and a cylindrical elastic jointing sleeve upon the tubular lower part, the tubular lower part extending downwards beyond the sleeve as a means of connection with the body of the plug next beneath and having holes therein communicating between the central cavity within and the surrounding annular space beneath the sleeve, and a valve in the body of the uppermost internal plug, the

- said valve opening downwardly, substantially as hereinbefore described.
19. Means for plugging the tubing of pressure wells formed of sections of tubing connected together by couplings, the bore of one of said couplings having a greater diameter than the normal bore of the tubing, comprising an internal plug for the tubing and dogs above the plug and connected thereto, the dogs being adapted with the plug for relative movement within the tubing, the dogs being adapted for engagement within the enlarged bore of the tubing on reaching it and for disengagement on admission of a releasing tool into the tubing, and the releasing tool, substantially as hereinbefore described. 80
- 10 20. Means for plugging the tubing of pressure wells, consisting of a mandrel disposed above and concentric with the well head casing and adapted at its lower end for engagement, an internal plug 85
- 20 for the tubing, elements upon the internal plug and connected thereto for connection with the lower end of the mandrel, the elements being normally subject to the action of a spring, and means consisting of a recess in the tubing bore by which 90
- 25 the lower end of the mandrel may be released by the said elements under the action of the said spring, substantially as hereinbefore described.
21. Means for plugging the tubing of pressure wells formed of sections of tubing connected together by couplings, the bore of one of which has a greater diameter than the normal bore of the tubing, consisting of an internal plug for the tubing which comprises a body part having a number of partially cylindrical recesses formed at 100
- 30 the top in circular series, upstanding dogs above the said body part having their lower ends of a partially cylindrical form adapted to be axially set into the said respective partially cylindrical recesses and to move pivotally therein, the 105
- 35 outer faces of the dogs being adapted in form to that of the tubing coupling having an enlarged bore, and the upper ends of the dogs being reduced and formed for engagement by a releasing tool and a spring by which the dogs are normally thrust outwards, substantially as hereinbefore described. 110
- 40 22. Means for plugging the tubing of pressure wells formed of sections of tubing connected together by couplings, the bore of one of which has a greater diameter than the normal bore of the tubing, consisting of an internal plug for the tubing which comprises a body part, upstanding dogs above the said body part and pivotally connected thereto, said dogs having the same form 115
- 45 and a shoulder on the outer face to engage within the tubing coupling having an enlarged bore, and having a recess on the inner side and reduced upper ends, and a spring by which the dogs are normally thrust outwards, substantially as hereinbefore described. 120
- 50 23. Means for plugging the tubing of pressure wells formed of sections of tubing connected together by couplings, the bore of one of which has a greater diameter than the normal bore of the tubing, comprising an internal plug, dogs above the plug and connected thereto, the dogs being adapted with the plug for relative movement within the tubing and being adapted for engagement within the enlarged bore of the tubing on reaching it, and a mandrel adapted at its lower end to engage the dogs within the normal bore of the tubing, and means for supporting the mandrel in position above and concentric with the 125
- 55 well head casing, and means for snubbing-in the 130
- 60 24. An internal plug for tubing in pressure wells, comprising the tubing, a body adapted to be passed into the tubing and adapted for free movement axially within the tubing on the body being released at the well head, a cylindrical elastic jointing sleeve upon the said body, the said sleeve being accessible to the pressure in the well, and means for locating and holding the said body within the tubing, comprising a locking device upon the said body and a coupling sleeve for adjacent sections of the tubing, said sleeve having an internal diameter larger than the normal bore of the tubing. 135
- 65 25. An internal plug for tubing in pressure wells, comprising, a body adapted to be passed into the tubing and to be relatively movable axially therein when released at the well head, the body having a lower tubular part, a cylindrical elastic jointing sleeve upon the body, and means for locating and holding the said body within the tubing, comprising a locking device on the body and a coupling sleeve for adjacent sections of the tubing, said sleeve having an internal diameter 140
- 70 larger than the normal bore of the tubing, and a valve in the upper part of the said body by which communication is open through the body. 145
- 75 26. Means for plugging the tubing of pressure wells, the bore of one of the constituents of which tubing is enlarged to form an annular recess, comprising an internal plug having an external elastic jointing sleeve thereon accessible to the well pressure and a locking device above the plug and secured to it that is adapted with the plug for axial movement within the tubing on release at the well head, the locking device being also adapted for engagement within the annular recess in the bore of one of the constituents of the tubing on passing into it and being also adapted for disengagement. 150
- 80 27. Means for plugging the tubing of pressure wells, the bore of one of the couplings of the tubing having a greater diameter than the normal bore of the tubing, comprising an internal plug for insertion within the tubing, and means for locating the internal plug within the tubing, comprising dogs disposed above the plug and connected thereto, the dogs being adapted for engagement within the enlarged bore of one of the couplings having a greater diameter than the normal bore, the said internal plug and connected dogs being adapted for free axial movement within the tubing on release of the dogs from engagement. 155
- 85 28. An internal plug for tubing in pressure wells, comprising a cylindrical elastic jointing sleeve, the internal cylindrical surface of which is exposed to the well pressure, and mechanical means at the well head by which the internal plug may be located and held in determined position with reference to an external packer located in the well head casing, in the running-in and withdrawal of the tubing. 160
- 90 29. An internal plug for tubing in pressure wells, comprising a body, part of which is of tubular form and open at its lower end, a cylindrical elastic sleeve upon the said tubular part, an internal annular cavity in the sleeve, a cylindrical inelastic sleeve with the annular cavity, and transverse holes extending through the tubular part of the body and the cylindrical inelastic sleeve. 165
- 95 30. An internal plug for tubing in pressure wells, comprising a body, part of which is of 170

tubular form and open at its lower end, a cylindrical elastic sleeve upon the said tubular part, an internal annular cavity in the sleeve, a cylindrical inelastic sleeve within the annular cavity, transverse holes extending through the tubular part of the body and the cylindrical inelastic sleeve, and a spring device disposed between the cylindrical inelastic sleeve and the cylindrical elastic jointing sleeve by which outwardly directed pressure is applied from within the latter.
